UNITED STATES PATENT OFFICE.

WILLIAM H. BROWNELL, OF BROOKLYN, NEW YORK.

DESIGN FOR A PLAQUE.

SPECIFICATION forming part of Design No. 13,973, dated June 12, 1883.

Application filed April 4, 1883. Term of patent 7 years.

To all whom it may concern:

Be it known that I, WILLIAM H. BROWNELL, of Brooklyn, Kings county, New York, have invented a new and original Design for a 5 Plaque, of which the following is a specification.

Figure 1 of the drawings is a plan view of the face of my plaque design; Fig. 2, a cross-sectional elevation on line *x* *x* of Fig. 1.
10 The plaque consists of a plate or disk having a central concave background, B, of dull or roughened appearance, surrounded by an annular band, C, of smooth-appearing contrasting surface, inclosed by a peripheral bead, D.

Having thus described my invention, what I 15 claim as new, and desire to secure by Letters Patent, is—

A design for plaques, consisting of a circular concaved plate or disk provided with an annular peripheral bead or flange, and having 20 a central background within the concave, of dull or roughened appearance, surrounded by an annular contrasting surface of smooth appearance, substantially as described and shown.

WILLIAM H. BROWNELL.
